UNITED STATES PATENT OFFICE

ALONZO ALDRICH, OF BELOIT, WISCONSIN

STEAM FITTING

Application filed April 13, 1923. Serial No. 631,858.

My invention relates to steam fittings, particularly steam fittings for use in connection with drying cylinders of paper making machines.

5 One of the objects of the invention is to provide a simple, practical and effective steam fitting, particularly of the class mentioned.

Another object of the invention is to permit 10 the adjustment of the fitting so as to secure effective drainage of the drying cylinder.

Referring to the drawings, Fig. 1 is a side elevation of a drying cylinder equipped with 15 the steam fitting embodying my present invention;

Fig. 2 is an end elevation of the same;

Fig. 3 is a side elevation partly in section of a portion of the device; and

20 Fig. 4 is an end elevation of the same.

Referring to the drawings, I show a drying cylinder 1 which is for use in a paper making machine and is shown mounted in frame pieces 2 and 3, the cylinder ends having 25 hub portions 3^a, 3^b. A steam inlet 4 is provided at one end on a head 1^a to let steam into the interior 5 of the drying cylinder. A drain pipe 6 is also shown extending into the same end of the cylinder and extended down 30 in the interior to the bottom of the same in order to act as a siphon or suction tube to remove moisture from the interior of the cylinder.

The steam inlet 4 connects with a downwardly extending steam supply pipe 8 which is understood to be suitably connected for supplying steam to the interior of the cylinder 1 to heat the same. To permit adjustment of the cylinder 1 relatively to pipe 8 an inlet pipe connection 9 is provided and pipes 8 and 9 are provided with cooperating joint pipe forming members 10 and 11, whereof the member 10 has a conical face 12 and the member 11 a cup face 13, in which the face 12 may 45 fit with a suitable layer of packing or other material 14 in between, bolt 15 and spring 15^a holding these parts together to make a tight joint. The pipe connection 9 is preferably formed as a part of a connecting member 23 which is held tight to head 1^a of

cylinder 1 by bolts 15^c controlled by springs 16, and passing through two arms 17, 17 on said member 23. Pipe 6 extends through member 23 and into head 18 to which it is secured by bolt 19. Head 18 is stationary but 55 rotatably adjustable and has a disk member 21 which cooperates with a disk 22 on member 23, disk 21 having a pointer or arrow 24 and member 22 having graduations 25 so that the relative position of said members 21 and 22 may be shown. Thus by turning the member 18 the position of the drain pipe 6 in cylinder 1 may be changed, and also the position of said pipe may be indicated. Thus if a change is made in the connection to the 60 drain pipe or if adjustments are made in the drying cylinder or in the pipe connections, a workman may put the drain pipe 6 back in just the position it was previously, by adjusting member 21 so that arrow 24 65 comes into register with the same graduation 25. Hence the placing of the drain pipe 6 in a wrong position, that is in some position other than a position at the bottom of cylinder 1, is avoided, and the adjustment 70 of said pipe to the right place is always secured, thereby always assuring the withdrawal of moisture from the cylinder 1 in the most efficient manner. The adjustment 75 of member 21 is permitted by means of circular slots 29 and bolts 30 adapted to pass through said slots.

In order to permit adjustment of the drying cylinder 1 and other parts an adjustable joint is made between drain outlet or discharge pipe 31 and member 23. This consists of a cone shaped member 32 and a cup shaped member 33, into which member 32 may fit with intervening packing 34. This joint is held tight by bolt 35 and spring 36.

The joint between cylinder head 1^a and member 23 is held against sidewise motion by fingers 17^b on arms 17 and 17^a on member 23 engaging annular surface 1^b on ring 1^c on head 1^a.

It will be understood that changes and modifications may be made without departing from the spirit of the invention.

What I claim is:

1. The combination with a rotatable tubu- 100

lar member, of a jointed connection with the end of the same comprising a member having engaging fingers adapted to engage an annular surface on said rotatable tubular member, and spring means holding said fingers in position to engage said annular surface.

6. The combination with a rotatable tubular member, of a jointed connection with the end of the same comprising a member having engaging fingers adapted to engage an annular surface on said tubular member, spring means holding said fingers in position to engage said annular surface, and steam inlet 10 and drain pipes connected with said second mentioned member by joints permitting relative adjustment between said member and said pipes.

7. The combination with a rotatable tubular member, of a connecting member at one end of the same, a drain pipe carried by the connecting member and extended into said tubular member and having an adjustable connection with said connecting member so 20 as to permit adjustment of said pipe in said tubular member and a water outlet pipe having a jointed connection with said connecting member, and means for adjusting said drain pipe relatively to said connecting member, 25 irrespective of the position of adjustment of said member relatively to said water outlet pipe.

8. The combination with a rotatable tubular member, of a connecting member at one 30 end of said tubular member, a drain pipe carried by said connecting member and extending into said tubular member, said drain pipe being mounted in said connecting member for angular adjustment, a head at the outer end 40 of said connecting member, said drain pipe being secured to said head and said head being rotatable relatively to said connecting member to permit angular adjustment of the drain pipe, and a water outlet pipe having a 45 connection with said connecting member.

9. The combination with a rotatable tubular member, of a connecting head at one end of said rotatable tubular member and spring controlled means for holding said connecting 50 member against the end of said rotatable tubular member, said spring controlled means including threaded bolts and cooperating springs whose tension is controlled by said bolts, and also including fingers tending to 55 prevent lateral displacement of said connecting member relatively to said tubular member.

10. The combination with a rotatable tubular member, of an elongated connecting member at one end of said tubular member, the 60 longitudinal axis of said connecting member being in alignment with said tubular member, a drain pipe carried by said connecting member and extending into the tubular member, said drain pipe being mounted in said connecting member for angular adjustment, and

a pair of pipes flexibly connected to said connecting member at longitudinally spaced positions thereon.

7. The combination with a rotatable tubular member, of an elongated connecting member at one end of said tubular member, the longitudinal axis of said connecting member being in alignment with said tubular member, a drain pipe carried by said connecting member and extending into the tubular member, and a pair of pipes flexibly connected to said connecting member at longitudinally spaced positions thereon.

8. The combination with a rotatable tubular member, of a connecting member therefor, and a pair of pipes connected at spaced positions to said connecting member, the connections for said pipes to said connecting member being flexible and independent of each other.

In witness whereof, I hereunto subscribe my name this 28th day of March, A. D., 1923.

ALONZO ALDRICH.
